R. C. REYNOLDS

SIFTING DEVICE

Filed Aug. 1, 1923

UNITED STATES PATENT OFFICE.

RAYMOND C. REYNOLDS, OF MUNCIE, INDIANA.

SIFTING DEVICE.

Application filed August 1, 1923. Serial No. 654,978.

To all whom it may concern:

Be it known that I, RAYMOND C. REYNOLDS, a citizen of the United States, residing at Muncie, in the county of Delaware and State of Indiana, have invented certain new and useful Improvements in Sifting Devices, of which the following is a specification.

This invention relates to sifting devices, 10 and has especial reference to appliances of this kind, as used in foundries.

In foundry work, there is the general use of the well known riddle consisting of a coarse sieve adapted to be manually manipulated by the moulder. In this practice, 15 the sand having been sifted into the mold flask, the riddle is emptied of its screenings and temporarily lain aside. After the mold will have been tamped and completed, 20 the riddle is again taken in hand by the moulder and the above described manipulations are repeated in the work of making up succeeding molds. Besides the physical strength exerted, there is consumed a con- 25 siderable amount of time in thus handling the riddle, and moreover, it is not unusual for the riddle to become damaged by being knocked about, or to become misplaced, thereby being not at all times in reliable 30 condition or within easy reach.

To provide means to facilitate the rapid and expeditious handling and deposit of the body or filling sand in the flask, and for the sifting or riddling of the top course 35 sand for completing the mold, is the object of the present invention. The invention contemplates the arrangement of a riddle or sieve supported for operation above the flask, and connections whereby the riddle 40 may be swung to and retained at position above, or at position removed from, the flask.

My invention is embodied in the new construction, combination, and arrangement of 45 parts shown in the annexed drawings and described in the following specification. The invention is defined in the appended claims.

In the drawings, the several parts of the

invention are identified by suitable characters of reference applied to them in the different views, in which—

Figure 1 is a top plan view of my improved sand sifting device.

Figure 2 is a side view of the invention.

Figure 3 is a vertical cross section view taken on the line 3—3 in Figure 2.

Figure 4 is a vertical cross section view taken on the line 4—4 in Figure 2.

Figure 5 is a view showing the position occupied by the invention, installed for use at the ordinary type of foundry bench.

Figure 6 is a modified form of riddle bottom or screen in which a raised peripheral edge or wall is used, as distinguished from the flat type screen or bottom shown in Figures 1 and 2.

The mechanism for carrying my invention into effect comprises a support and rocker bar retained for movement in a housing or guide block that is adapted to be secured at suitable position in proximity to the molding flask, a holder element, designated as a riddle frame, a riddle or screen removably retained in said frame, connections between the said frame and the rocker bar to permit the frame to be swung to and retained at extended or operative position, or to the retracted or inoperative position.

The utility of, and advantages accomplished by, the above described combination and arrangement of parts will become apparent as the specification of my invention proceeds.

The housing block may be made of any suitable metal, aluminum being the metal preferred, and it consists of the parallel side walls A and A retained at spaced distance apart by the integrally formed web B. Each of the flanges C is provided with a suitable aperture through which ordinary cap screws or bolts 1 and 1 may be passed and secured to a shelf or other suitable form of support 2 above the moulder's bench 3.

On suitable cross pins located at the power portion of the front end, and at the upper

portion of the rear end of the housing, are journaled the free running rollers F and G respectively.

The rocker bar H is about fifteen inches 5 in length, and three quarters of an inch thick and is disposed between the walls of the housing. Longitudinal grooves in the sides of the rocker bar minimize its weight and provide the lateral faces H¹ which have free bearing against the inner sides of the said walls. The top and bottom faces 10 of said rocker bar have bearing against the rollers G and F respectively.

Disposed on the rear portion of the rocker bar to serve as a buffer or cushion when the rocker bar is pulled to the limit of its forward movement, is a spring J. This spring may rest loosely on the bar and is retained thereon by a cross pin H² the 15 protruding ends of which constitute abutments for the said spring. Similarly there is provided a spring K on the forward portion of the rocker bar, and which has bearing against the head member. This 20 head member of the rocker bar may be of the integral form shown and is provided with the arms L and L.

The riddle frame may be made of any desired general form or size, and of any suitable material. It preferably consists of a 30 sheet metal annular band M with beaded wire bound top rim, and an inturned bottom flange M¹. The function of this frame is to retain removably, the riddle or sieve 35 screen proper. Divers forms of riddle frame and screen bottoms may be used, depending upon the nature of the sand, and of the molding to be done. A modified form of screen is shown in Figure 6.

A form of screen useful and effective for 40 general purposes consists of a metal ring O of suitable diameter to be easily inserted into the frame band M and to rest on the flange M¹. The ends of the wires O¹ constituting the screen fabric, are secured to 45 the ring O. Secured to the band M of the riddle frame, is a connector head having arms P and P which rest on top of the arms L and L of the rocker bar head. 50 These pairs or arms are joined together in the manner of a hinge, by a loose pin Q having a nut Q¹ on its lower end and to bear against the underside of the lower arm L, and a coil spring R between the 55 upper arm P and the head Q² of the said pin. The tension provided by this spring, and the action of the recess in the lower arm P, as it engages the tooth L¹ of the lower arm of the rocker bar head, is to 60 hold the riddle frame at the position of alignment with the rocker bar, as shown in Figure 1 and Figure 2. The location of the said recess with reference to the tooth L¹ is such that when the riddle is swung

to the dotted line position (see Figure 1) 65 it is yieldably retained at that position. To stiffen the wall band M of the riddle frame a reinforcing or stiffening bar O² may be fastened by the bolts S that connect the connector head to the said band. 70

My invention, installed for practice, as 75 shown in Figure 5, has the housing block fastened to the usual shelf 2 of the moulder's equipment. The moulder's flasks 4 are disposed on the bench 3 at such location that when the riddle is at the extended position shown, the center of the flask is substantially midway between the ends of the travel forward and back, of the riddle. 80

While making up the mold for the castings to be formed, the riddle is disposed at the dotted line position shown in Figure 85 1, and in which position, the space above the flask is unobstructed, so that the moulder may, with his shovel, deposit in the flask, the bulk of the sand needed. When the mold is in readiness to receive the finer sand, the operator grasps the handle M¹ of the riddle frame and swings same to the forward or extended position where it 90 is filled with its quota of sand. The operator then again grasps said handle M² of the riddle and moves same backward and forward. The weight of the riddle and its contends being borne by the rocker bar 95 bearing against the rollers F and G, a free and easy movement of the rocker bar is assured. The natural effort of the operator in moving the riddle back and forth is unobstructed by any stiffness or rigidity in 100 the device, and the action imparted to the riddle is of an undulating or raising and lowering character, so that there is an effective rocking or tilting motion, resulting in the expeditious screening of the sand. 105 Shock or impact at the housing as the limits of the movement of the rocker bar are reached, is prevented by the action of the buffer springs J and K.

By the use of my invention, as just described, the shifting or riddling of the sand is accomplished effectively and very speedily. To discharge from the riddle, the 110 screenings, the screen is lifted with its contents, free from the riddle frame and after 115 being emptied is simply replaced at its normal position. The frequency with which the screen is removed and emptied is determined by the size of the mesh and the character of the sand. Ordinarily the emptying of the riddle screen occurs about every fourth or fifth mold constructed. The screen may be provided with a handle O³ by 120 which it may be easily lifted from the riddle frame. 125

A sand sifting device constructed in accordance with my invention is very economical of manufacture, and is capable of

being economically packed for transportation, and is easy to install. The housing, and also the rocker bar and head are of form not only effective as to strength and 5 to perform the functions required of them, but are capable of being cast in molds of the simplest form. A minimum amount of machine work is required and preparing the parts, and the device is rugged and durable 10 and not liable to derangement or breakage.

Claims:

1. A sifting device, comprising a housing block, a rocker bar mounted loosely 15 therein, a riddle frame, a screen retained removably in the riddle frame, and a yieldable connection between the rocker bar and the riddle frame capable of retaining the riddle frame at varied positions of angularity to the rocker bar.
2. A sifting device, comprising a housing adapted to be secured at suitable position adjacent to the flask into which the sand is to be deposited, a rocker bar mount-

ed in said housing for reciprocative movement, a riddle, and a yieldable connection between the rocker bar and the riddle capable of retaining the riddle in registration or out of registration with the said flask.

3. A sifting device, comprising a housing adapted to be secured at suitable position adjacent to the flask into which the sand is to be deposited, a rocker bar disposed loosely between the walls of said housing, a roller journaled in the housing at its 35 forward portion and upon which roller the rocker bar is adapted to rest, a roller journaled above the rocker bar, and a roller journaled below the rocker bar at location at the rearward portion of the housing, a 40 riddle, yieldable connections between the rocker bar and the riddle to retain the riddle at varied positions of angularity to the rocker bar, and a buffer element between each end of the rocker bar and the said 45 housing.

In testimony whereof I affix my signature.

RAYMOND C. REYNOLDS.
